CLAIM

The ornamental design for a kabob pet treat, as shown and described.

DESCRIPTION

FIG. 1 is a front, bottom, left side perspective view of a first embodiment of a kabob pet treat according to the new design;

FIG. 2 is a back, top, right side perspective view thereof;

FIG. 3 is a left side elevation view thereof;

FIG. 4 is a right side elevation view thereof;

FIG. 5 is a bottom plan view thereof;

FIG. 6 is a top plan view thereof;

FIG. 7 is a front elevation view thereof;

FIG. 8 is a back elevation view thereof;

FIG. 9 is a front, bottom, left side perspective view of a second embodiment of a kabob pet treat according to the new design;

FIG. 10 is a back, top, right side perspective view thereof;

FIG. 11 is a left side elevation view thereof;

FIG. 12 is a right side elevation view thereof;

FIG. 13 is a bottom plan view thereof;

FIG. 14 is a top plan view thereof;

FIG. 15 is a front elevation view thereof;

FIG. 16 is a back elevation view thereof;

FIG. 17 is a front, bottom, left side perspective view of a third embodiment of a kabob pet treat according to the new design;

FIG. 18 is a back, top, right side perspective view thereof;

FIG. 19 is a left side elevation view thereof;

FIG. 20 is a right side elevation view thereof;

FIG. 21 is a bottom plan view thereof;

FIG. 22 is a top plan view thereof;

FIG. 23 is a front elevation view thereof; and,

FIG. 24 is a back elevation view thereof.

The broken lines in the drawings illustrate portions of the kabob pet treat that form no part of the claimed design.
